ATTACHMENT FOR LOOMS.

1,006,559.

Specification of Letters Patent. Patented Oct. 24, 1911.

Application filed March 22, 1910. Serial No. 550,856.

To all whom it may concern:

Be it known that I, VICTOR H. JENNINGS, a subject of the King of Great Britain, residing at Worcester, in the county of Worcester and State of Massachusetts, have invented a new and useful Attachment for Looms, of which the following is a specification.

This invention relates to looms, and while capable of general use, is particularly adapted for, and useful in, looms for weaving narrow fabrics.

It has been found in practice that as the warp spreads backwardly from the heddles and is under considerable tension it constantly has a tendency to force the heddles not only outwardly, but forwardly, particularly at the two edges of the fabric. This is not a serious matter ordinarily, with wide cloth, but with narrow fabrics and especially those which are tightly woven, the tension is so great and the resultant forces act on such a relatively large proportion of the warp threads that it constitutes a serious handicap in the manufacture of the goods. The results of this difficulty are that the heddles as they move back and forth come into engagement with each other and restrict their proper operation, at the same time, practically grinding the contacting surfaces so that the warp has a great tendency to break. The wastage from this cause amounts to a very large percentage, particularly in certain classes of goods. This has been a serious loss and has greatly increased the cost of narrow fabric goods, particularly that which is tightly woven and has a high tension on the warp.

The principal object of this invention is to provide a simple, inexpensive, and convenient construction which shall efficiently guard against this interference of the heddles, and at the same time reduce very materially the breakage, and consequently the waste due thereto.

Further objects and advantages of the invention will appear hereinafter.

Reference is to be had to the accompanying drawings, in which—

Figure 1 is a transverse vertical sectional view of a loom showing a preferred embodiment of this invention, and Fig. 2 is a plan of the same.

The invention is shown as applied to a loom having a frame 10 provided with har-

nesses 11 and heddles 12 for guiding the warp 13 as is well understood. A member or frame 14 is pivoted at points 15 on a stationary part of the frame 10 and extends to a point beyond the forward heddle. This frame is shown as comprising two arms which extend from the opposite sides of the frame 10 and in this case are turned inwardly at 16, because the invention is shown as applied to the weaving of narrow fabrics. It will be understood, however, that when used for a fabric the full width of the loom the inner arms 17 of these members will be farther apart than is shown in Fig. 2. These arms 17 are shown as parallel and as supporting a plurality of parallel rods 18. Each of these rods extends from one edge of the warp to the other and extends between two sets of parallel heddles, consequently, these rods are spaced apart a distance equal to the space between the sets of heddles. This member 14 can be made stationary if desired, but it is preferred to have it pivoted on the frame 10 so that it will be free to have a slight motion. In this case it is always supported by the lower harnesses, and its slight motion does not interfere with the operation of the heddles. Its weight is so small that it does not interpose any appreciable obstacle in the way of the operation of the various parts of the machine.

On account of having the rods located as set forth they keep the heddles from being forced forward, and at the same time the arms 17 tend also to keep the outer heddles in proper alignment transversely of the loom. An important feature of advantage, however, is that all the heddles of each set are kept in proper position, and no heddles can come into contact with the heddle of the next set. It has been found in practice that by keeping the heddles separate in this way the amount of breakage is reduced by a very large percentage, and consequently the wastage is also greatly reduced. This has proven a very important feature in certain classes of narrow fabrics and is applicable to weaving in general.

While I have illustrated and described a preferred embodiment of the invention, I am aware that many modifications can be made therein by any person skilled in the art without departing from the scope of the invention as expressed in the claim. Therefore I do not wish to be limited to all the details

of construction herein shown and described, but

What I do claim is:—

In a loom, the combination with the frame, 5 harnesses, and heddles, of a pair of movable parallel arms pivoted on the frame and extending to a point beyond the forward heddle, and a series of parallel bars supported by and between said arms just be- 10 low and transverse to the warp, each bar

extending between two sets of heddles for keeping them separated.

In testimony whereof I have hereunto set my hand, in the presence of two subscribing witnesses.

VICTOR H. JENNINGS.
